UNITED STATES PATENT OFFICE.

THOMAS F. MOORE, OF SYRACUSE, NEW YORK, ASSIGNOR TO MOORE TRENCH MACHINE CO., OF SYRACUSE, NEW YORK, A CORPORATION OF NEW YORK.

TRENCHING APPARATUS.

Specification of Letters Patent. Patented Apr. 16, 1918.

1,263,096.

Application filed December 29, 1915. Serial No. 69,217.

To all whom it may concern:

Be it known that I, THOMAS F. MOORE, a citizen of the United States of America, and resident of Syracuse, in the county of Onondaga, in the State of New York, have invented new and useful Improvements in Trenching Apparatus, of which the following, taken in connection with the accompanying drawings, is a full, clear, and exact 10 description.

This invention relates to certain improvements in trench machines adapted to be used in excavating and re-filling trenches for sewers, water and gas mains and other unders 15 ground conduits which are to extend considerable distances through straight or more or less undulating and tortuous routes and frequently require the use of sheathing plank arranged edge to edge vertically along 20 and against the side walls of the trench and suitably braced to retain said walls against caving in during the process of excavation and laying of the conduits.

In many instances, particularly in large 25 cities, these trenches extend along routes which intercept highways and other lines of travel, and one of the main objects of my present invention is to construct a trestle along the line of the trench in such manner 30 as to permit the use of temporary crossovers at the high-ways or other intercepting lines of travel without in any way disturbing the structural elements of the trestle when once assembled for use.

Another object is to provide a clear open 35 space from top to bottom lengthwise through the trestle for the free manipulation of conveying and hoisting apparatus carried by the trestle or operating in the 40 trenches.

A further object is to provide one or more traveling cranes movable lengthwise of and co-operating with the trestle for use in placing and displacing the sheathing and other 45 materials used in the formation and reinforcement of the trench throughout its length.

A still further object is to provide a trestle which is made up of similar length- 50 wise units of suitable length capable of being easily and quickly installed in operative position end to end and to connect the meeting ends in such manner that either section may be deflected vertically or horizontally 55 at a greater or less angle to the adjacent

section to conform to the contour or route along which the trench extends.

Other objects and uses relating to specific parts of the apparatus will be brought out in the following description.

60

In the drawings—

Figure 1 is a perspective view of a trench and a portion of my improved apparatus mounted in operative relation thereto looking toward the power house at one end of 65 the trestle.

Fig. 2 is a side elevation, partly broken away, of one end of the same apparatus including the power house, traveling conveyer and one of the traveling cranes.

70

Fig. 3 is an end view of one of the trestle sections showing the trench in cross section, and also showing the traveling crane in operative relation to the trestle, as used in driving the sheathing plank into the ground.

75

Fig. 4 is a top plan of the upper portion of the crane and adjacent portion of the guide rail on the trestle.

Fig. 5 is an enlarged transverse sectional view of the upper portion of the trestle and 80 adjacent portion of the crane in traveling contact therewith, a portion of the traveling conveyer being also shown in elevation, as operatively mounted upon the ridge rail of the trestle.

85

Fig. 6 is an enlarged side elevation, partly in section, of the meeting ends of the ridge rails of the trestle sections showing the manner of securing said ends together.

Fig. 7 is a horizontal sectional view taken 90 on line 7—7, Fig. 6.

Fig. 8 is a top plan, partly in section of the central portion of the ridge rail of one of the trestle sections and reinforcing members therefor, showing the connections for 95 the brace bars for stiffening the ridge rail against buckling.

Fig. 9 is an enlarged detail sectional view through a portion of the traveling conveyer taken on line 9—9, Fig. 2.

100

Fig. 10 is an enlarged side elevation, partly in section, of the upper portion of the rear end of the trestle, opposite that at which the power house is located, showing the buffer stop for the traveling conveyer 105 and adjacent sheave over which one of the cables for operating the conveyer is passed.

The entire trestle is constructed so as to span the trench, as —A—, transversely and is adapted to be moved as a unit lengthwise 110

thereof along and upon suitable rails or stringers —1— which are supported upon the surface of the ground at opposite sides of the trench and extend lengthwise thereof the full length of the trestle and some distance beyond its opposite ends for receiving and supporting a power house or car —2—.

The trestle is preferably composed of portable sections secured together end to end, one of said sections being shown more clearly in Fig. 2, and comprises opposite upwardly converging legs —3— united at the top by a cross bar —4—, Figs. 1 and 3, and a guide rail or ridge-beam —5— having one end supported by the central portion of the cross bar —4—, and its other end projected horizontally some distance therefrom and supported by brace bars —6— having their upper ends connected in a manner hereinafter described to the central portion of the rail or beam —5—, and their lower ends secured by slip connections —7— to the corresponding legs —3— to allow the legs and brace bars to be relatively adjusted when necessary to conform to the lateral adjustment of the legs for trenches of different widths.

The legs —3— and cross bar —4— are also braced against relative movement when adjusted for use by opposite brace bars —8— converging upwardly from the central portions of the legs —3— to points at opposite sides of, and some distance from the ridge beam or rail —5—, the upper ends of the braces —8— being pivoted by bolts —9— to the cross bar —4— while their lower ends are pivoted to clamping members —10— which are adjustable along and upon their respective legs —3— and are adapted to be frictionally clamped in their adjusted positions by bolts —11—.

The legs —3— are pivotally connected by bolts —12— to opposite ends of the cross bar —4— so as to permit them to be adjusted transversely to span trenches of different widths by simply loosening the clamping members —7— and —10— and readjusting them to conform to the adjustment of the legs, after which they are tightened to firmly lock their respective brace bars thereto, it being understood that the connection between the upper ends of the brace bar —6— and ridge rail —5— is sufficiently flexible to allow the necessary adjustment of such brace bars.

The connection between the upper ends of the brace bar —6— and ridge rail or beam —5— comprises lengthwise reinforcing members —13— rigidly secured by bolts —14— to opposite faces of the web of the beam —5— substantially midway between the ends of said beam, and outstanding brackets —15— secured to the outer faces of the central portions of the reinforcing members —13— by bolts —16— together

with tubular stays —17— interposed between the central portions of the brackets —15— and adjacent faces of the reinforcing members —13— to better resist the strains upon the brackets, the upper ends of the brace bars —6— being applied to the apexes of the brackets —15— where they are held in place by the bolts —12— passing through the sleeves and also through registering apertures in the reinforcing members —13— and beam —5—.

The legs —3— of each pair, together with their connecting cross bar —4— and braces —8— constitute what may be termed one of the main upright supports for the ridge rail or beam —5— and are disposed in the same transverse vertical plane, the lower ends of the legs being provided with suitable shoes or bearings —18— resting upon and movable along their respective rails —1—.

The height of the trestle from the top of the rails —1— to the under side of the ridge beam —5— is sufficient to allow an ordinary loaded wagon or car to pass across the track and under the ridge beam.

It is now clear from the foregoing description that the pairs of brace bars —6— and —8—, as well as the legs —3— of each trestle section are located some distance apart at opposite sides of the overhead ridge beam —5— so that when the several sections of the trestle are assembled they afford a clear unobstructed space longitudinally thereof from end to end and from the tops of the rails —1— to the under side of the ridge beam through any part of which conveyers, buckets and other objects may be moved freely into and out of and along the trench at any height within such space without interference with any part of the trestle.

It is equally evident that by connecting the diagonal braces —6— to the bases of the legs —3— and to the central portions of the ridge beam —5— in the manner described, it not only serves to hold said beam at substantially right angles to the transverse vertical plane of the legs —3— against lateral buckling, but also leaves a clear open space between said diagonal braces and the upright standard or support of the next adjacent trestle section of sufficient dimensions to allow the passage of ordinary vehicles and cars therethrough, as for example at the intersection of streets or other lines of travel of pedestrians and vehicles, the only requirement being to provide the trench with necessary crossovers.

The ridge rail —5— of each trestle section preferably consists of a steel I-beam arranged edgewise vertically and having its base flanges —19— constituting lengthwise guide rails for receiving and supporting a traveling conveyer —20— having each of its ends provided with opposite pairs of rollers

—21— which are movable along and upon the guide rails or flanges —19—, as shown more clearly in Figs. 2 and 5.

The traveling conveyer —20— may be of

- 5 any suitable construction capable of receiving and supporting a fall block —22— to which the load, as a bucket —23— shown by dotted lines in Fig. 2, may be attached, said fall block being controlled by a cable —24—
 10 passing over sheaves —25— on the traveling conveyer —20— and another sheave on the fall block and having one end attached to said fall block and its other end passed around a sheave —26— on the rear end of 70
 15 the trestle, Fig. 10, and returned to the front end of said trestle over a sheave —27— and attached to an operating drum —28— in the power house, said cables also serving to draw the conveyer rearwardly when the fall block with or without the load thereon is 75 elevated and locked in the conveyer.

Another cable —29— has one end attached to a separate drum —30— in the power house and its other end passed over a sheave 25 —31— on the front of the trestle and attached to the front end of the conveyer, as shown in Fig. 2.

The power house is preferably made in the form of a car mounted on the track 30 —1— and carrying suitable motive power for operating the drums —28— and —30— and is also provided at its rear end with an upright standard —3— for supporting the front end of the ridge beam of the adjacent 35 trestle section so that the car constitutes a part of the trestle work which may be moved as a unit along and upon the track as the work upon the trench progresses.

Each cross bar —4— preferably comprises a pair of oppositely arranged juxtaposed angle bars of steel having their horizontal flanges at the top and facing each other, as shown in Fig. 6, and held in spaced 40 relation by interposed sleeves —32— for receiving clamping bolts —33— by which the angle bars are held in operative relation 45 and in parallelism.

In order that the trestle sections may be easily and quickly assembled end to end, and 50 the meeting ends of their ridge rails held in exact registration so that the supporting rails for the conveyer may be practically continuous, the adjacent ends of the webs of the ridge rails or beams are cut away 55 relatively short distances longitudinally to form recesses —34—, the combined length and vertical height of the recesses being sufficient to receive the cross bar —4— which is passed therethrough, but in practice these 60 recesses are made slightly longer and wider vertically than the corresponding cross sectional dimensions of the cross bar so as to permit the beams to be deflected slightly vertically and horizontally at the joint at an 65 angle to each other if desired to conform

to the contour of the ground and direction of the route along which the trestle extends.

The portions of the beam sections at the top and ends of the recesses are preferably straight and disposed at right angles to each other to allow such portions of the beam to rest flatwise upon and against the adjacent flat portions of the cross bar vertically when the beam sections are arranged in the same straight line or deflected horizontally relatively to each other. 75

When the beam sections are properly assembled upon the cross bar end to end, they are firmly clamped together by fish plates —35— applied to opposite sides of the webs 80 of the adjacent ends thereof and secured thereto by bolts —36—, said plates being provided with out-turned flanges —37— engaging opposite faces of the cross bar —4— and clamped thereto by the same bolts —33— 85 which pass through the sleeves —32—.

Each of these fish plates is provided with a central opening —38— of substantially the same size and form as that formed by the recesses —34— in the adjacent ends of the 90 beam sections —5— and registering therewith for receiving the cross bar 4.

The upper edges of the clamping plates —35— above the openings —38— are provided with out-turned flanges —39— closely 95 fitting against the under side of the top flanges as —19— of the ridge beam —5— for additionally holding the meeting ends of the beams in alinement.

These plates are preferably made of bendable metal, such as boiler iron or malleable castings, so as to permit a slight bending thereof, particularly at the junctions of the flanges —37— with the main body in case it is necessary to deflect either one of the 100 adjacent beams at an angle to the other, such relative adjustment being further facilitated by making the openings for the bolts —36— in the web of the beam sections slightly 105 longer than the diameter of the bolts and 110 also making the openings in the cross bar for the bolts —33— slightly larger than such bolts.

In this manner, a slight flexing connection is established between the cross bar 115 and adjacent ends of the ridge beam sections serving to permit said sections to be deflected at a slight angle relatively to each other without destroying the alinement or continuity of the guide rails along and upon 120 which the conveyer —20— is movable.

Channel bars —40— are secured by bolts —41— to the tops of their respective beam sections —5— and extend from end to end thereof with their side flanges up-turned 125 to form guide rails for the upper portion of a traveling crane —42— having its lower end provided with roller bearings —43— movable along and upon a separate rail or stringer —1'—, the latter being extended 130

along and upon the ground parallel with and just outside one of the main rails —1— for the trestle.

This traveling crane may be of any suitable construction, but preferably comprises a main upright —44— extending from the rail —1— some distance above the top of the trestle where it is provided with a laterally projecting arm —45— overhanging the top of the trestle and pivoted at —46— to the main upright —44— so as to permit its free end to rest by its own weight upon the guide rail —40— and allow such free end to automatically adjust itself to any slight variations in the height of the derrick as the crane is moved along the same, said pivotal connection between the arm —45— and upright —44— also serving to permit the arm to be swung vertically into and out of engagement with the guide rail —40— when placing the crane in operative relation to the trestle, or removing it therefrom.

In order that the upper end of the traveling crane may be held against lateral movement relatively to the ridge beam —5—, and at the same time to allow it to move freely back and forth along the guide rail —40— without liability of binding, the inner end of the arm —45— is elongated in the direction of length of the trestle and is provided at its opposite ends with vertical and horizontal rollers —48— and —49—, as shown more clearly in Fig. 5, the roller —48— resting upon the upper face of the web of the guide rail —40— close to the inner face of one of the upstanding flanges thereof, while the roller —49— engages the outer upright face of the same flange, thus holding the upper portion of the crane against undue transverse movement relatively to the guide rail —40— and beam —5—, while the spacing of the rollers of each set some distance to the opposite sides of the longitudinal center of the arm —45— enables this part of the crane to move freely along and upon the guide rail —40— without liability of binding, the roller bearings —43— on the lower end of the upright —44— being also spaced a considerable distance apart at the opposite side of the longitudinal center of the upright —44— to give ample support for the crane against longitudinal rocking movement.

55 The traveling conveyer —20— comprises a pair of upright hangers —50— spaced some distance apart in parallelism lengthwise of the trestle and in substantially the same vertical plane as the beam —5—, the upper ends of said bars being extended upwardly at opposite sides of the base flange of the beam —5— for receiving the rollers —21— which ride upon the upper faces of said base flanges and serve to support the entire conveyer.

The lower ends of the hangers —50— terminate in a horizontal plane substantially midway between the tracks —1— and the under side of the beam —5— and are provided with platforms —51— extending inwardly toward each other, but spaced a sufficient distance apart to receive the bucket —23— between them, said platforms being also extended longitudinally some distance to opposite sides of the hangers —50— to 75 form convenient supports for an operator.

The inner ends of the platforms are provided with upturned extensions —52— which are connected by a rigid cross bar —53—, thereby bracing the lower ends of 80 the hangers against relative lateral movement, the inner ends of said platforms being spaced apart to form a bucket opening and side buffers, and are additionally supported by diagonal braces —54— connecting the upper ends of the extensions —52— to the upper portion of the hangers —50—.

Additional horizontal bars —55— are secured to opposite faces of the hangers —50— in parallelism with and some distance below the beams —5— for further stiffening the conveyer frame and forming a suitable support for the locking mechanism for the fall block —22— and load carried thereby.

The bars —55— are extended some distance rearwardly beyond the rear hanger —50— for receiving and supporting a sheave —56— for the cable —24—, and terminate in a buffer —57— co-operating 100 with a corresponding buffer —58— on a bracket —59— which is rigidly secured to the rear end of the ridge beam —5— of the trestle for limiting the movement of the conveyer in that direction.

The bars —55— are provided with pendant plates —60— in spaced relation transversely for receiving between them the fall block —22—, said plates being provided with lengthwise slots —61— for receiving a locking pin —62— which is adapted to be engaged by the usual hook on the upper end of the fall block for holding said fall block and load carried thereby upon the carriage.

This locking pin —62— is mounted upon a 115 hand lever —63— which is pivoted at —64— to the bars —55— so that when desired the lever —63— may be operated by hand to release the locking pin —62— from locking engagement with the fall block —22—, as 120 for example in the operation of lowering the bucket —23—.

When the traveling conveyer is operated along inclined portions of the trestle, and particularly with one or both operating 125 cables slack, the momentum or gravity tends to carry it beyond the place where it is desired to stop, and in order to retard this excessive movement, I have provided a brake-shoe —65— movable into and out of 130

engagement with the lower face of the ridge beam —5—, as shown more clearly in Fig. 2, said brake-shoe being attached to the upper end of a vertically moving rod —66— which is guided on the front end of the conveyer —20— and has its lower end connected to a pedal lever —67— also mounted on the conveyer near the adjacent platform —51— within convenient reaching distance 10 of the operator so that by pressing down upon the pedal end of the lever —67—, the brake-shoe —65— may be forced into frictional engagement with the under side of the beam —5— for stopping the conveyer 15 at the desired point in its travel.

The crane —42— is provided with suitable hoisting mechanism —68— having a cable —69— passing over a sheave —70— on the top of the crane and carrying a drop weight or hammer —71—, by which the 20 sheathing, as —a—, of the trench may be driven into the ground.

It is evident, however, that the hoisting device of the crane may be used for any other 25 purpose to which it is adapted, as for example in withdrawing the sheathing, or in handling timbers and other materials used in the formation of the trench.

In assembling the various parts of the 30 trenching machine, the tracks —1— and —1'— are first laid along opposite sides of the proposed trench uniform distances apart, after which the power car —2— may be placed thereon and moved to the desired position.

The legs —3— of the trestle sections before being raised to operative position are 35 adjusted to conform to the width of the track upon which such trestle section is to be mounted, it being understood that the entire trestle section, including the beam —5—, braces —6— and —8—, legs —3— and cross bar —4— are properly secured together to form a unitary structure in which 45 the plate —35— is secured to the cross bar and to the adjacent end of the beam, leaving an open space between opposite ends of the plates for receiving the adjacent end of the beam of the next succeeding trestle section 50 by removing the bolts —33— which are to secure said succeeding section to the plates.

The trestle section next adjacent the power house is then placed with its shoes —18— upon the track —1— and the free 55 end of the section is then raised to a horizontal position and the entire section then adjusted along the track until engaged with the upright —3'— of the power car to which it is secured by suitable bolts.

60 In like manner the next succeeding trestle section is placed in operative position upon the track and its free end elevated into engagement with the adjacent end of the plates —35— and secured thereto by the previously 65 removed bolts —33—.

In a similar manner any number of sections may be added in sequence to complete the trestle to any length desired, it being understood that the conveyer —20— may be placed upon the beam —5— of the first trestle 70 section as soon as such section is secured in operative position, or may be similarly placed upon any one of the succeeding sections.

It is also evident that the conveyer may 75 be set up in operative relation to the trestle during the progress of building or at any time after the trestle is completed. The manner of assembling and operating the remaining parts of the device are believed to 80 be described with sufficient clearness to enable anyone skilled in the art to construct and use the same.

What I claim is:

1. In a trench machine, a trestle composed 85 of lengthwise sections secured together end to end, each section comprising a pair of upwardly convergent legs, a cross bar pivotally connected to the upper ends of said legs to permit the latter to be rocked inwardly and 90 outwardly about said pivots to correspond to different widths of trenches, braces having their upper ends attached to the cross bar and their lower ends provided with slip connections with the legs, a guide rail having one end centrally secured to the cross bar, additional braces having their upper ends secured to the guide rail intermediate its ends and their lower ends attached by slip connections with the legs some distance 95 below the points of attachment of the first-named braces, and a conveyer movable along and upon the guide rail.

2. In a trench machine, a trestle composed 105 of lengthwise sections secured together end to end and each section comprising upwardly convergent legs, a cross bar pivotally connecting the upper ends of the legs to permit the latter to be rocked about the pivots to conform to trenches of different widths, an 110 overhead lengthwise guide rail centrally secured near one end to the cross bar, brace rails having their upper ends attached to the guide rail intermediate its ends and their lower ends provided with slip connections 115 with the legs, and a conveyer movable along and upon the guide rail.

3. In a trench machine, a trestle composed 120 of lengthwise sections secured together end to end, each section comprising opposite upward legs, a cross bar connecting the upper ends of the legs, a lengthwise guide rail secured near one end to the cross bar, opposite brace bars having their upper ends attached to said guide rail at a point some distance 125 from the cross bar, and connections between the lower ends of the brace bars and legs, in combination with a conveyer movable along and upon the guide rail.

4. In a trench machine, a trestle composed 130

- of lengthwise sections secured together end to end, each section comprising opposite upright legs, a cross bar pivotally connected to the upper ends of said legs, brace bars in the same transverse plane as the legs and cross bar and having their upper ends attached to said cross bar, connections between the lower ends of the braces and legs, a lengthwise guide rail secured near one end to the cross bar, additional brace bars extending upwardly and longitudinally from the lower ends of the legs, connections between the lower ends of the additional brace bars and legs, and separate connections between the upper ends of the brace bars and guide rail at a point some distance from the cross bar.
5. In a trench machine, a trestle composed of lengthwise sections secured together end to end, each section comprising opposite upright legs, a cross bar connecting the upper ends of the legs, a guide rail for supporting a traveling conveyer secured near one end to the center of the cross bar, brackets secured to and projecting from opposite sides of the rail some distance from the cross bar, brace bars having their upper ends attached to said brackets, and slip connections between the lower ends of said brace bars and legs.
6. In an apparatus of the character described, the combination of a track having its rails running along opposite sides of the trench, a trestle mounted on said rails and having an overhead lengthwise ridge-beam, said trestle having an unobstructed lengthwise passage extending from the rails to the ridge-beam and from end to end of the trestle, and a traveling conveyer movable along and upon said beam.
7. In an apparatus of the character described, a trestle comprising an overhead

lengthwise ridge-beam composed of sections arranged end to end and having their meeting ends provided with recesses wholly between the lower and upper edges thereof, a cross bar extending through said recesses, means for securing the beams and cross bar against relative movement, and spaced supporting legs for the opposite ends of the cross bar.

8. In an apparatus of the character described, a trestle comprising an overhead lengthwise ridge beam composed of sections arranged end to end and having their meeting ends provided with recesses wholly between the lower and upper edges thereof, a fish plate secured by separate bolts to the adjacent ends of the beam sections and provided with an opening therethrough registering with said recesses, a cross bar passed through said opening and recesses, means for securing the cross bar to the fish plate, and supporting legs for opposite ends of the cross bar.

9. In an apparatus of the character described, the combination of a track having its rails running along opposite sides of the trench, a trestle mounted on said rails and composed of sections having overhead lengthwise ridge-beams flexibly connected end to end, a traveling conveyer movable along and upon the ridge-beams, and provided with base-platforms spaced apart transversely to form a bucket opening and buffers for a bucket or load carried by said conveyer.

In witness whereof I have hereunto set my hand this 20th day of December, 1915.

THOMAS F. MOORE.
